PIVOTED BAR BENDING APPARATUS HAVING MEANS FOR RELIEVING EXCESS CLAMPING PRESSURE AT REGION OF BEND

Claude H. Warren and Gerald M. Pollard, Vallejo, Calif.

Application June 2, 1953, Serial No. 359,238

3 Claims. (Cl. 153—40)

(Granted under Title 35, U. S. Code (1952), sec. 266)

This invention may be manufactured and used by or for the Government of the United States of America for governmental purposes without the payment of any royalties thereon or therefor.

This invention relates to apparatus and methods for bending metal shapes and, more in particular, to method and apparatus for bending flat bar edgewise.

As is well known, numerous different machines have been developed for bending and working the various forms of metal blanks, and among such machines are included the well-known sheet metal bending brakes, the plate bending rolls, pipe and rod benders and many other types. However, in most of these machines, the metal is bent transversely of its longitudinal axis and the bend produced is across the relatively narrow thickness of the metal. On the other hand, there are some types of work in which it is desirable to bend the metal edgewise or, in other words, to bend it along its relatively large width. Of course, if the metal to be bent is sufficiently narrow or pliable, no difficulty will be experienced, but where the work piece is relatively wide and thick, any such attempt usually has resulted in fracturing or tearing along the outside radius of the bend.

One particular operation in which it would be most profitable to accomplish this edgewise bending is the shaping of copper bus bars, such as are used in extremely long sections as electrical contact wipers in buildings, or, in long electrolytic processing tanks and the like. Very frequently, it is necessary to form a shallow dip or rise in the lengths of these bus bars and, of course, they require any number of right-angle bends at structural corners. However, attempts to produce these bends have met with such consistent failure that the prevailing and, as far as is known, the only practice is to braze, silver solder, or bolt separate sections together to form the desired shape. As will be readily apparent, any such mechanical coupling of the separate lengths constitutes a relatively tedious operation and represents a considerable unnecessary waste of time and labor. Further and even more important than such economic considerations is the fact that the electrical characteristics of bus bars coupled together in such mechanical manners have been found to be depreciated and, most probably, this is due to the necessity of applying heat for the brazing or soldering. At least, it is a certainty that local applications of heat, such as are used in silver soldering, create localized strains or weak points in the metal which, subsequently, produce fractures when subjected to vibrations or other physical disturbance.

In view of these disadvantages, some attempts have been made at bending bus bars, but, as previously indicated, when the bar to be bent is of a conventional, commercially-used size, such as 4" x $\frac{3}{8}$ " bar, these attempts invariably have resulted in such fracturing of the outer radii of the bends as to render the bars unsatisfactory for use.

There are several possible explanations for the failure of the art to have evolved a commercially practical method

2

of bending these bars. In the first place, it is common bending practice to clamp the object to be bent against a stationary support and then to swing or move the bending beam about the bending fulcrum or shaft. Although such a manner of bending may be suitable for producing transverse bends across relatively thin work pieces, it is not satisfactory when wide bars and the like are to be shaped. Apparently, the difficulty lies in the fact that such a bending requires an excessive stretching of the metal about the bending shaft and, when the bar is a wide one, there is not a sufficient flow of metal from the inner to the outer radius to avoid tears or fractures being produced in this outer radius. Whatever the physical reason may be, it is clear that attempts to bend bars that are clamped to stationary plates have not proven successful. Another difficulty inherent in the bending of any flat stock lies in the fact that the full width of the stock must be clamped to a support so as to maintain the width and prevent the metal from crimping or folding against the shaft around which the bending is taking place. Such a clamping, however, produces its own difficulties in that, during the bending, portions of the metal adjacent to the shaft thicken or upset to such an extent that the inner radius of the bar becomes tightly bound between the clamp, the bar support and the shaft. When the bar becomes bound in such a manner, a shearing effect is produced longitudinally of the bar due to the fact that the outer portions of the bar are relatively free to move and the obvious result is that the bar gives, or, in other words, fractures at its weakest point, which obviously is its outer radius because that portion reduces in thickness as the bar is being bent.

It is, therefore, an object of the present invention to provide apparatus and method for cold-bending bar stock in an edgewise direction.

More specific objects are to provide apparatus for bending bar edgewise in which the bar is clamped to its support in a manner capable of minimizing stretching of the metal during the bending and, further, to provide a means for relieving the clamping pressure during the bending a sufficient amount to avoid binding of the bar beneath the clamp.

Other objects are to provide an unusually simple and expeditious manner and means for bending bar edgewise without producing excessive internal strains or fractures in the bar stock.

According to the present invention, the bending apparatus includes a table on which the bar stock is clamped and supported during the bending, and projecting outwardly of this table, is a shaft around which the bar is bent. One of the features of the invention is that the table is rotatably driven to carry the bar about the shaft so that there is a minimum stretching of the metal stock during the bending and, of course, the clamp which secures the bar flat against the table also rotates with the table. In the preferred forms, means, such as a heavy roller, is disposed in a laterally-spaced position from the shaft for engaging the outer edge of the bar and pressing it against the shaft during the bending, this means also being mounted for rotation with the table. The rear or trailing portion of the bar is braced or supported against any lateral swinging movement so as to provide the equal and opposite force necessary to produce the bend.

In operation, after the bar is tightly clamped in position on the table and the outer edge forming roll is brought to bear against it, the table is rotatably driven to carry the bar arcuately about the shaft. As would be expected, as the inner radius of the bar is pressed against the shaft, it automatically thickens or upsets, and, in view of this, another feature of this invention lies in the manner in which binding due to such thickening is prevented. Briefly, this feature involves the provision

of means for relieving the clamping pressure in direct proportion to the degree of the bend that is being made, such relief being effected by permitting the clamp to rise a sufficient amount to compensate for the thickening. Although a skilled operator might be able to manually release the clamp the desired amount, the invention contemplates automatic means for accomplishing this result, and the automatic means is controlled by the table rotation so as to insure a direct relationship between the degree of rotation and the amount of clamping pressure release. In the preferred form, the clamp is rotatably mounted on the bending shaft and its clamping pressure is provided by a special nut that threadedly engages the shaft. Rotation of this nut in one direction produces the desired clamping effect, while rotation in the opposite direction provides the clamping release. This rotation in the opposite direction is achieved through the use of a lever which engages the nut at one end and engages the rotating table at the other, the result being that, as the table rotates, the nut is turned and the pressure relieved. Most suitably, the pitch of the nut's threads is so designed that a certain rise or release of the clamp is effected when the nut is rotated through a 90 degree arc.

Other features of the present invention are more concerned with the structural and mechanical aspects of the apparatus and, since an understanding of them requires a rather detailed description, they are not considered appropriate for present generalized analysis.

The preferred embodiment of the invention is illustrated in the accompanying drawings of which Figs. 1 and 2 are plan and side views, respectively, while Figs. 3, 4 and 5 are vertical sections taken along lines III-III, IV-IV and V-V of Fig. 1, and Fig. 6 a plan view similar to Fig. 1 showing the position of the bending parts at the completion of bending operation.

Referring to the drawings, the functional elements of the machine all are mounted in a single cast steel frame 1 which, as may be noted, is bolted to and supported by a fabricated steel platform foundation 2, such an arrangement combining all of the machine components into a single unit that can be moved about in the shop as desired. Casting 1, as shown in the sectional drawings, is hollow and, further, it is formed with a portion of its top wall cutaway in a particular manner to form a well, or recess 3 in which is mounted a table 4. In a manner which will be described, this table is adapted to be rotated about its central vertical axis, and, to permit this rotation, the inner edge of well 3 is specially shaped.

Preferably, hydraulic means are provided for rotating the table because such means assure a steady, constantly-applied and controlled pressure and, as may be noted in Fig. 4, these hydraulic means include a pair of oppositely-driven pistons 6 and 7 mounted as shown in cylinders 8 and 9 which, most suitably, are bolted to frame 1. Each of these pistons is provided, in the conventional manner, with compression retaining rings 11 as well as suitable leather piston seals 13, and the hydraulic fluid to drive the pistons is admitted into their cylinders through conduits 16 and 17. Most suitably, power for the pistons is provided by a self-contained hydraulic pump unit which includes a constant displacement pump 18 which draws its supply from an oil reservoir 19. Power for the pump may be supplied by a 5 H. P. 220/440 volt 3 phase alternating current motor 21, although power of such a magnitude probably is beyond normal demands, and, if desired, suitable control mechanism, including solenoid valves, limit switches, etc. may be provided to facilitate operations.

The need for the two pistons 6 and 7 is, as might be anticipated, to produce a reversing rotary motion in table 4 and, for this purpose, both of these pistons are connected to the table through a connecting rod 22 (Fig. 1), and actually both pistons are formed as integral extensions of a central shaft 23 which, in turn, is coupled

to the connecting rod. Most suitably, shaft 23 is coupled to the connecting rod by means of a connecting rod pin 24 which is deeply anchored in a recess formed in the shaft and which projects outwardly of the shaft through a relatively heavy ring member 26 mounted on the shaft. The opposite end of connecting rod 22 is secured to table 4 by another connecting rod or pin 28 which projects upwardly from the rod into a close fit with a deep bore extending upwardly from the base of table 4.

As a result, when hydraulic power is applied to left-hand piston 6, table 4 is rotated in a clockwise direction (Fig. 1) and when the power is applied to the other piston the table moves back to its original position in the opposite direction. During this movement, it will be noted that a substantial portion of the periphery of table 4 bears against the casing wall so as to provide additional support for the table and render the machine more rigid and strong. In addition, as would be expected, the compound leverage provided by connecting rod 22 is capable of developing more than sufficient power for most any desired bending operation.

The remaining elements of the apparatus deal more directly with the actual gripping and bending of the bar to be shaped and, generally, these include (Fig. 5) a stationary shaft 31 around which the bar is bent, clamping mechanism 32 for clamping the bar to table 4 and bar-holding mechanism 33 adapted to engage the outside of the bar and press it against bending shaft 31.

As to the more specific details of these elements, shaft 31 is formed at its lower end with a laterally projecting flange 34 by means of which it is bolted to a downwardly projecting lip portion of frame 1, the shaft also having a central portion 36 of relatively large diameter and an upper portion of reduced diameter. This upper portion, as may be noted, is formed with smooth-walled lower bar-engaging extent 37, while the upper extent of this portion is formed with specially shaped threads 38 the functioning of which will be described later. Central portion 36 extends upwardly through frame 1 and also through table 4, the table being rotatably mounted on the shaft in any suitable manner, such as by means of a frictionless bearing ring, and the shaft as a whole is secured in position by a retaining ring 41 which may be fastened directly to the shaft by elements such as cap screws 42. The important thing to note about this structure is that the shaft itself is stationary, while table 4, as well as other elements mounted on it, are rotatable about it.

As to these other rotatable elements, their function is to cooperatively provide what has been referred to previously as bar clamping mechanism 32 and, as may be seen, they include a clamping plate 43 which fits rotatably about portion 37 of the shaft and a special nut 44 adapted to mesh with threads 38. When a section of bar stock is to be bent, it first is placed on table 4 beneath clamping plate 43, after which nut 44 is tightened against the plate to effect the clamping pressure.

As will be appreciated, as the bar is being bent, some force must be exerted laterally against its outer edge to hold it tightly up against the portion of the shaft around which it is to be bent and, in the illustrated form, this force is provided by bar-holding mechanism 33. The functional part of this mechanism is provided by a hardened roller 46 (Fig. 5) which is rotatably mounted on a central shaft 47, this roller being held in position by a retaining ring 48 which may be secured to the shaft by a set screw 49. Also, as will be apparent, the position of roll 46 should be adjustable in accordance with the width of the bar that is being bent, and such adjustability is provided by an elongate feed screw 51 threadedly meshed with the lower portion of shaft 47. The inner end of feed screw 51 is reduced in size and engaged in a circular recess 52 formed in table 4, while the outer end of the feed screw is provided with means by which the screw can be rotated to move shaft 47 and its associated elements toward and away from bending

shaft 31. In addition, it can be appreciated that considerable force will be exerted on bending roll 46 during a bending operation, and one of the advantages of the present arrangement is that this force can be effectively absorbed by the shaft 47, its retaining ring 48 and feed screw, as well as by a feed screw retaining ring 53. Ring 53 engages a lateral flange 54 formed on the feed screw and the assemblage is secured in position by a suitable lock nut 56 threadedly engaged with ring 53 in the manner illustrated in Fig. 5.

During a bending operation, it is desirable to provide additional elements to engage the bar and hold it in a proper relationship with respect to the shaft around which it is being bent. One of these elements is an additional clamping plate 57 which, as may be noted in Figs. 1 and 3, is mounted on table 4 so as to rotate with the table. Clamping plate 57 is keyed to table 58 so as to be movable to various appropriate positions with respect to the platform, and, after the plate has been adjusted, it may be clamped to the table by bolts 59. In addition, the clamping plate mounts a separate gripping plate 61 to actually engage the bar, and this plate is movable toward and away from such engagement by screws 62. The obvious purpose of this additional clamping mechanism is to securely engage the bar at a spaced distance in advance of clamping mechanism 32 and to thereby assist mechanism 32 in holding the bar flatly against the table surface.

The other additional bar-engaging element is used to abut the trailing end of the bar and prevent this trailing end from swinging arcuately as the clamped portion of the bar is being rotatably carried and bent around bending shaft 31. Such an element is provided by block 64 (Fig. 1) which may be bolted in a stationary position to the upper surface of frame 1 in the manner shown. If desired, this block can be adjustably mounted and also can be provided with a removable and replaceable wearing surface, such mechanical refinements being common knowledge and needing no description.

As has been noted, the present invention provides several advantageous features, such for instance as the fact that the bending is accomplished by clamping the bar to be bent to a rotatable table and then rotating the table to carry the bar about the bending shaft. This particular feature is advantageous because it minimizes the metal stretching which otherwise would occur if the metal were clamped to a stationary table and then forced, by means of an arcuately-swinging beam or the like, about a bending shaft. As will be obvious, when relatively wide and thin bars are being bent any such minimizing of stretching is extremely important to avoid excess attenuation and weakening of the portions subject to the most stretch.

However, another equally important feature which also minimizes stretching and reduces fracturing is the fact that the present clamping mechanism 32 is so arranged as to permit a release of the clamping pressure as the bending progresses. This release, of course, must be accomplished by unscrewing special nut 44 but, in the present invention, the unscrewing of this nut is performed automatically and at such a controlled rate that the pressure release is directly proportional to the degree of rotation of the table. Such an automatic release is provided by coupling shaft 47 of bar holder mechanism 33 to nut 44 by means of a slotted lever 63. With these two elements so coupled, it will be appreciated that any arcuate swing of lever 63, caused by the rotation of the table and its shaft 47, will be translated into a rotational movement of nut 44. Obviously, the arrangement is such that a swing of the table in a clockwise or bending direction unscrews nut 44 to permit clamping plate 32 to rise and relieve its clamping pressure. The purpose in relieving the pressure is to avoid a binding of the bar between the clamping plate, the bending shaft and the table, such a binding being due to

a thickening or upsetting along the inner radius of the bar as it is being bent. According to present thinking, when such a binding occurs, portions of the bar along the inner radius are held tightly against the stationary shaft, while the portions exterior to this inner radius are relatively free to travel with the table and the clamp. As a result, a very substantial pull is exerted along the inner radius and this pull may be visualized as a shearing action capable of acting longitudinally of the bar to eventually cause a fracturing of the metal at its weakest joints which will be along its outer attenuated radius.

In the present apparatus, any such binding is avoided by a controlled release of the clamping pressure, and very close control of this release may be accomplished by forming threads 38 with such a special pitch that rotation of the table through any particular arc will result in a desired unscrewing action of nut 44. According to the present practices, threads 38 are formed with a 50° angle and a pitch of .304". Translating this pitch into rotary motion, it can be seen that the nut and clamping plate rise approximately .076 inch during a 90 degree arcuate swing of the table and its associated elements.

Other features of the invention which also are of importance include the hydraulic compound drive by means of which the rotational travel of the table can be closely controlled; the adjustable mounting and support of bar holding roller 46 and, from an overall viewpoint, the general arrangement of the structure which provides sturdiness, compactness, portability and economic operation.

Briefly reviewing the operation of the machine, a bar to be bent is placed on table 4 by sliding the bar into position beneath hold-down plate 43 and feed screw 51 then rotated to move roller 46 into contact with the exterior edge of the bar. Depending upon the thickness of the bar, it may be necessary to back off nut 44 and manually lift lever 63 so as to permit the bar to be slipped in beneath hold-down plate 43. At this point the bar is tightly held between roller 46 and shaft 31, so that nut 44 and screws 62 may be screwed down to clamp the bar tightly against the table. Also, it should be made certain that the trailing edge of the bar abuts block 64 so that, as the bar is being bent, the block will apply such equal and opposite force as is necessary to produce the bend. With the bar so engaged the hydraulic control mechanism is actuated to drive piston 6 and rotate the table in a bar-bending, clockwise direction. After the bend is completed, the bar may be taken out by using wrench lever 63 to remove nut 44 and permit the removal of hold-down plate 43. Screw 62 also should be released to loosen gripping plate 61, whereupon the bent bar can be slid out. If the bend is not too sharp, it will not be necessary to remove nut 44 and the bar can be slipped out simply by backing off of this nut and loosening gripping plate 61. The hydraulic control mechanism may be reversed to drive piston 7 and cause the table to return to its initial position. Such a bending operation is, as has been stated, a continuous one and one in which the necessary bends are produced without fracturing, as well as without any application of deleterious heat.

However, to avoid any misconception, it should be noted that, although the above description has been slanted toward a machine that is adapted for bending copper bus bars, it is contemplated that the machine also could be used for bending other metal stock, and, in fact, the machine described above has sufficient power to bend even wider and thicker stock than the 4" x $\frac{3}{8}$ " copper bus bars usually encountered.

Obviously, many modifications, both in structure and use may occur to those skilled in metal working and, to the extent that such modifications include the broader concepts of the invention, they are within its contemplated scope. For example, it would not be necessary to couple lever 63 to shaft 47 in the manner illustrated,

Instead, the table could be formed with a separate projection onto which the lever could be coupled, or, perhaps, there are other equivalent mechanisms which could be substituted in entirety for the lever itself. In fact, such a lever is not absolutely necessary for proper operation of the apparatus and, if the operator is sufficiently skilled, he can release the pressure of nut 44 manually by use of a wrench or the like. In other words, the invention is more concerned with economically producing smooth, unfractured bends by eliminating metal stretching and binding to as great a degree as possible, than it is with the mechanical details of the mechanisms that facilitate the movements required.

We claim:

1. Bar-bending apparatus comprising a table, means for rotating the table, a bar-bending shaft projecting outwardly of the table, adjustable means rotatable with the table for pressing a table-supported bar against said shaft, a clamp rotatably mounted on the shaft for pressing said bar against the table, means threadedly mounted on the shaft for pressuring said clamp, fixed bracing means abutting the trailing portion of said bar and holding said bar against lateral movement for producing a bend in the bar as the rotated table carries it about said shaft, and lever means coupling together said table and said clamp pressuring means, rotation of said lever means with said table rotating said threaded pressuring means sufficiently during the bending operation to relieve excess clamping pressure caused by bar upsetting.

2. Bar bending apparatus comprising a table, hydraulic means for rotating the table, stationary bar-bending shaft projecting outwardly of the table, adjustable roller means rotatable with the table for pressing a table-supported bar against said shaft, a clamp rotatably mounted on the shaft for pressing said bar against the table, means threadedly mounted on the shaft for pressuring said clamp, fixed bracing means abutting the trailing portion of said bar and holding said bar against lateral movement for producing a bend in the bar as the rotated table carries it about said shaft, and lever means

coupling together said table and said clamp pressuring means, rotation of said lever means with said table rotating said threaded pressuring means during the bending period to relieve excess clamping pressure, said pressure relief being controlled by the relationship between the degree of rotation and the pitch of said threaded pressure means.

3. Bar-bending apparatus comprising a table, means for rotating the table, a stationary bar-bending shaft projecting outwardly of the table, adjustable means rotatable with the table for pressing a table-supported bar against said shaft, a clamp rotatably mounted on the shaft for pressing said bar against the table, clamp-pressuring means mounted on and rotatable about the axis of said shaft, said pressuring means having an inclined-plane surface functioning upon rotation of said clamp-pressuring means to forcibly move the pressuring means axially along said stationary shaft whereby to vary the pressure exerted by said means on said clamp, fixed bracing means abutting the trailing portion of said bar and holding said bar against lateral movement for producing a bend in the bar as the rotating table carries it about said shaft, and lever means coupling together said table and said clamp-pressuring means, rotation of said lever means with said table rotating said clamp-pressuring means sufficiently during the bending operation to relieve excess clamping pressure caused by bar upsetting.
